UNITED STATES PATENT OFFICE

162,261

GAEMENT HANGER

James W. Tuma, Muncie, Ind.

Application April 24, 1950, Serial No. 9,435

Term of patent 14 years

(Cl. D33—8)

To all whom it may concern:

Be it known that I, James W. Tuma, a citizen of the United States, residing at Muncie, in the county of Delaware and State of Indiana, have invented a new, original, and ornamental Design for a Garment Hanger, of which the following is a specification, reference being had to the accompanying drawing, forming part thereof.

Figure 1 is a front elevational view of a garment hanger, showing my new design, and

Figure 2 is a side elevational view thereof.

I claim:

The ornamental design for a garment hanger, as shown.

JAMES W. TUMA.
